US00D844569S

(12) **United States Design Patent** (10) Patent No.: **US D844,569 S**
(45) Date of Patent: **** Apr. 2, 2019**

(54) **ELECTRICAL SWITCH**

(71) Applicant: **ABB Schweiz AG**, Baden (CH)

(72) Inventor: **Frank Brenk**, Hausach (DE)

(**) Term: **15 Years**

(21) Appl. No.: **35/500,806**

(22) Filed: **Oct. 9, 2015**

(80) **Hague Agreement Data**

Int. Filing Date: **Oct. 9, 2015**

Int. Reg. No.: **DM/087825**

Int. Reg. Date: **Oct. 9, 2015**

Int. Reg. Pub. Date: **Apr. 15, 2016**

(51) LOC (11) Cl. **13-03**

(52) U.S. Cl.

USPC **D13/158**

(58) **Field of Classification Search**

USPC D13/138, 139.1-139.4, 123, 110, 107,
D13/152; 361/641, 601, 696; D14/365;
174/50.52

CPC H02B 1/52; H02B 1/20
